APPARATUS FOR TESTING LOCOMOTIVES

Walter F. Collins, Scarsdale, N. Y.

Application July 20, 1938, Serial No. 220,406

4 Claims. (Cl. 73—51)

This invention relates to apparatus for testing locomotives.

In locomotive testing, a laboratory locomotive is utilized, to determine among other things boiler efficiency, merits of any particular device or appliance, and economic value of fuel and its relation to boiler capacity. Three conventional test methods are in use, first, road tests involving the use of a dynamometer car and under road service conditions. Second, stationary dynamometer tests in which the locomotive machinery is run and the locomotive is worked throughout its range of its capacity, while the locomotive remains stationary. This permits all test measurements to be made with a degree of accuracy possible only in a stationary power plant. The stationary dynamometer test requires a special building, housing a means for supporting the locomotive so that its driving wheels may be rotated and the power absorbed and dissipated, together with a locomotive stationary dynamometer. Third, standing tests in which the machinery is disconnected and the boiler alone is operated, the steam generated being passed through the exhaust nozzle to produce the draft in the usual way.

Road tests are difficult to conduct, are costly and have a bad effect on operation due to steam failures, slow train movements, stalled trains and bad psychological effect on engineers and firemen. Stationary dynamometer tests are costly and few plants are built in this country and abroad, and these are not readily available to all railroads. Standing tests are generally resorted to in an endeavor to avoid the above trying experiences and high costs.

In a standing test the valves and the cylinder pistons are removed and the cylinder acts as an expansion chamber. Highly superheated steam is admitted to the cylinder at reduced pressure equal to the exhaust pressure, through the medium of a gate valve. These standing tests are inaccurate and do not simulate actual road conditions because boiler pressure is reduced to the proper exhaust or back pressure and no control of temperature is attempted.

In the operation of a locomotive in actual service a large portion of the energy of the steam is converted into work by the operation of the pistons and associated parts, resulting in a decrease in the pressure and temperature of the steam flowing through the system. Other losses by radiation and other causes also diminish the potential energy of the steam and the total energy loss is determined in road tests by a comparison

of the temperature, pressure and quality of the steam before entering and after passing through the cylinders as determined by instruments such as thermometers, pressure gages, calorimeters and the like.

Heretofore standing tests of locomotives have attempted the control of the pressure at the exhaust nozzle only, so that the escaping steam contains all the energy that in road operation is dissipated in the form of work, and as the amount of gas expelled from the smokebox by the exhaust nozzle and stack combination depends on the energy in the steam supplied rather than its weight, the results have been misleading.

In the operation of modern locomotives, the expansion of the steam in the cylinder is rarely carried to the point where saturation temperatures are reached or moisture exists in the exhaust steam, hence I have discovered that in the simulation of road conditions during a standing test it is only necessary to reduce the intrinsic energy of the steam by desuperheating as described, and abstract from the system an amount of steam equivalent to the water used for such desuperheating. Should it be desired to test conditions represented by extremely short cut-offs resulting in such low temperatures that moisture is found in the exhaust steam, additional instruments such as calorimeters would be required supplementary to those that I have described, but the contingency is so remote and the operation of such instruments so well known that further description is unnecessary for the exposition of my invention.

When the temperature of the exhaust steam is not controlled and the steam possesses a high degree of superheat, the steam exhibits a greater volume for a given back pressure than when it is used in the cylinders to work the pistons of a locomotive. This excess volume produces high velocity draft through the stack resulting in large quantities of excess air passing through the boiler and effecting the boiler efficiency and capacity so that road conditions are not even approximately simulated.

With the above in mind an object of the present invention is to provide, in a standing test, apparatus for controlling the temperature of the exhaust steam by desuperheating the superheated steam, through the medium of a spray of water mist in the cylinder and which is subsequently removed in its entirety. The standing test, with exhaust temperature thus controlled in accordance with the invention, produces a quicker, more

5 accurate and economical method for studies than hitherto possible because uniformity of conditions can be maintained, the effect of minor changes can be observed, a great many more 10 tests may be made in a given time than hitherto possible, and the actual road performance can be predicted, in the laboratory, without incurring either the difficulties of procedure or the uncertainty of road tests.

10 With the above and other objects in view the invention consists of certain novel details of construction and combinations of parts hereinafter fully described and claimed, it being understood that various modifications may be resorted to 15 within the scope of the appended claims without departing from the spirit or sacrificing any of the advantages of the invention.

In the accompanying drawings forming part of this specification,

20 Figure 1 is a fragmentary side elevation of a laboratory steam locomotive, with parts in section, equipped with apparatus for desuperheating the steam and controlling exhaust temperature, in accordance with the invention.

25 Figure 2 is a front elevation of the locomotive shown in Figure 1.

Figure 3 is a detail longitudinal sectional view taken on the line 3—3 of Figure 1.

30 Figure 4 is a detail longitudinal sectional view of the locomotive cylinder showing the location of the water spray nozzles for desuperheating the steam.

Figure 5 is a cross sectional view taken on the line 5—5 of Figure 4.

35 Figure 6 is a detail cross sectional view showing a modified form of the invention.

Referring now to the drawings in which like characters of reference designate similar parts in the various views, 18 designates a stationary 40 locomotive in which the pistons have been removed from the cylinders 11 and the valves have been removed from the valve chests 12. In carrying out the invention a tube 13 is disposed axially in each valve chest and discs 14 are welded 45 to the ends of the tube and to the valve bushings 15 in such manner that each tube and its discs permits some of the exhaust steam to pass from the respective cylinder through the front exhaust passageways 16 of the valve chest, as indicated 50 by arrows, and the remaining portion to pass through the rear exhaust passageways 17, of the valve chest, as also indicated by arrows, thus reducing pressure.

The tube and discs separate and prevent leakage 55 between superheated steam which enters the valve chest from the steam pipe 18 and passes into the cylinder through the passageways 19 and 20, and the steam, desuperheated by the hereinafter described water spray, which exhausts 60 from the cylinder through the exhaust passageways 20 of the valve chest and through the exhaust passageways 16, tube 13 and exhaust passageways 17 of the valve chest. The steam admitted to the valve chest through a valve 21 in 65 the steam pipe 18, is highly superheated steam reduced in pressure to that of the exhaust steam in a road test.

A plurality of spray nozzles 22 are arranged in stepped relationship in each cylinder 11 and 70 the respective pipes 23 from the nozzles are conducted through stuffing boxes 24 in the rear head 25 of the cylinder. The pipes are controlled by respective valves 26 and communicate with a water manifold 27 which is supplied with water 75 through a pipe 28 which is equipped with a water

5 meter 29. A pressure gauge 30 is connected to the water manifold. The highly superheated steam in the cylinder meets the water from the spray nozzles and flashes the water into steam. The water absorbs heat from the superheated 10 steam and reduces the temperature of the steam, that is, desuperheats the steam. The temperature of the desuperheated steam exhausting from the cylinder through the passageways 20 may be controlled to any predetermined degree, and is determined by the amount of water added to the steam by the sprays.

The additional steam created by the water spray must be bled off or extracted to attain results equivalent to a road test. Obviously any 15 increased amount of steam passing through the exhaust nozzle would increase the draft and increase the volume of air drawn into the fire box for combustion so that the boiler performance would not duplicate a road test.

20 For removing this excess steam created by the water spray, a bleed off or steam extraction pipe 31 is connected to the front and rear exhaust passages 32, best shown in Figures 2 and 3, which lead from the cylinders to the exhaust pipe and nozzle 33. In practice, an amount of steam equal to the spray water, indicated by the meter 29, is lead away through the pipe 31 and diverted from the exhaust nozzle. The quantity of steam bled off is controlled by a valve 34 in the bleed off pipe, best shown in Figure 1. A pressure gauge 35 and a thermometer 36 are located in the bleed off pipe or other suitable location in the system, to indicate respectively the pressure and the temperature of steam passing to the exhaust 35 nozzle.

By manipulation of the valves 26, arranged for operation using any number at one time, and regulating pressure of the water to obtain the best spray for the best temperature results, steam, 40 at pressure and temperature corresponding to the pressure and temperature experienced in a road test, and at the same volume, may be delivered to the exhaust pipe and nozzle for the creation of draft, and for the purpose of furnishing air for combustion in the fire box and expelling the products of combustion, such as gases, cinders and smoke, together with the exhaust steam to the atmosphere, by way of the stack 37.

In Figure 6 there is shown a modified form of 50 the invention in which the parts are the same as above described with the exception that instead of using the tube 13 and discs 14 the conventional piston valve 38 is blocked in the valve chest so that the desuperheated steam divides 55 and part passes through the front exhaust passageway 39, and part passes through the piston valve body to the rear exhaust passageway 40.

In operation, superheated steam designated as 60 100% at the steam pipe 18, is admitted to the valve chest 12 and from there passes through the valve bushing at the rear end of the valve chest and into the cylinder where it encounters the sprays and is reduced in temperature or desuperheated. The sprays add an "X" amount of 65 water and the 100% steam plus an "X" amount, which has been flashed into steam from the water, passes from the cylinder, part of the steam passing through the valve bushing at the front end of the valve chest and into the front exhaust passages, and part passing through the tube 13 and through the rear valve bushing and into the rear exhaust passages.

The purpose of directing the exhaust steam through both the front and the rear exhaust 75

passages is to reduce the exhaust pressure in a manner similar to that which takes place in actual road service when the valve spool is working and the steam is being used to drive the drive 5 wheels.

From the exhaust passages 32 the steam divides, part passing to the exhaust nozzle and part passing into the bleed off pipe 31 where an "X" amount of steam is extracted or bled off in 10 order that only the 100% steam originally furnished by the boiler, will go through the exhaust nozzle. This arrangement duplicates exactly the conditions that take place when steam is used during actual road service, or during road tests, 15 or during stationary tests when the pistons are used to convert the energy of the steam into work.

While the invention has been described in connection with locomotive testing, the scope of the 20 invention is intended to extend to industrial processes wherever there is a need for low temperature steam initially furnished at high temperatures.

From the above description it is thought that 25 the construction and operation of the invention will be fully understood without further explanation.

What is claimed is:

1. Apparatus for simulating actual road performance in the standing test of a locomotive 30 having a boiler, a cylinder, a valve chest, a connection between the boiler and valve chest, front and rear exhaust passages, a connection between the exhaust passage and the valve chest, and an 35 exhaust nozzle, comprising the combination of means for supplying a predetermined quantity of water to the cylinder for reducing the temperature of superheated steam in the cylinder, means in the valve chest for initially supplying 40 superheated steam to the cylinder at one end thereof and subsequently directing the steam, together with an added amount of steam flashed from the water, from the opposite end of the cylinder to both the front and the rear exhaust 45 passages simultaneously to reduce pressure of the steam, means connected to the exhaust passages for extracting an amount of steam equal to the steam flashed from the water, and means for delivering the resultant steam to the exhaust 50 nozzle.

2. Apparatus for simulating actual road performance in the standing test of a locomotive having a boiler, a cylinder, a valve chest, a connection between the boiler and valve chest, front 55 and rear exhaust passages, a connection between the exhaust passages and valve chest, and an exhaust nozzle, comprising the combination of a spray nozzle in the cylinder, a water supply pipe connected to said nozzle, a meter for measuring the water supplied to the nozzle through the pipe, said valve chest having valve bushings, 60 a stationary valve connected to the valve bush-

ings of the valve chest and adapted to supply superheated steam to one end of the cylinder and divide desuperheated steam from the opposite end of the cylinder into two paths respectively to the front and to the rear exhaust passages, a valve controlled bleed off pipe connected to the exhaust passages for extracting an amount of steam equal to the steam flashed from the water, and means for delivering the resultant steam to the exhaust nozzle. 5

3. Apparatus for simulating actual road performance in the standing test of a locomotive having a boiler, a cylinder, a valve chest, a connection between the boiler and valve chest, front and rear exhaust passages, a connection between 15 the exhaust passages and valve chest, and an exhaust nozzle, comprising the combination of a spray nozzle in the cylinder, a valve controlled water supply pipe connected to said nozzle, a meter for measuring the water supplied to the 20 nozzle through the pipe, said valve chest having bushings, a stationary valve connected to the valve bushings of the valve chest and adapted to supply superheated steam to one end of the cylinder and divide desuperheated steam from 25 the opposite end of the cylinder into two paths respectively to the front and to the rear exhaust passages, a valve controlled bleed off pipe connected to the exhaust passages for extracting 30 an amount of steam equal to the steam flashed from the water, a thermometer and a pressure gauge connected to the bleed off pipe for indicating the temperature and pressure of steam therein, and means for delivering steam at the pressure and temperature indicated by the thermometer and the pressure gauge to the exhaust 35 nozzle.

4. Apparatus for simulating actual road performance in the standing test of a locomotive having a boiler, a cylinder, a valve chest, a connection between the boiler and valve chest, a connection between the exhaust passages and valve chest, and an exhaust nozzle, comprising the combination of means for admitting steam 40 under pressure above atmosphere and temperature above saturation to the locomotive cylinder, means for introducing a spray of water into the locomotive cylinder, means for extracting the steam flashed from the water spray, which extracted steam represents the heat drop or 45 thermal value of the steam equalized in the cylinder where part of its thermal value or energy is transformed into mechanical energy and transmitted to the drive wheels during actual service conditions, means for passing exhaust 50 steam to the main exhaust passages of the locomotive for draft making purposes subsequent to extraction of the quantity of steam flashed from the water spray, and means for determining the 55 temperature and the pressure of the exhaust steam. 60

WALTER F. COLLINS.
